Primary Examiner — Andrew Kerr(74) *Attorney, Agent, or Firm* — Christensen O'Connor Johnson Kindness PLLC(57) **CLAIM**

The ornamental design for a beverage making machine, as shown and described.

DESCRIPTION

FIG. 1 is a left side elevational view of a beverage making machine according to my new design;

FIG. 2 is a front elevational view thereof;

FIG. 3 is a right side elevational view thereof;

FIG. 4 is a rear elevational view thereof;

FIG. 5 is a top-rear-right perspective view thereof;

FIG. 6 is a top-front-right perspective view thereof;

FIG. 7 is a top-front-left perspective view thereof;

FIG. 8 is a bottom-rear-left perspective view thereof; and,

FIG. 9 is a bottom-front-right perspective view thereof.

The broken lines indicated by short lines show portions of the beverage making machine that form no part of the claimed design. The broken lines indicated by alternating long lines and pairs of short lines define boundaries of the claimed design and form no part thereof.
